(57) **CLAIM**

The ornamental design for the device to break dried pasta, as shown and described.

DESCRIPTION

FIG. 1 is a top perspective view of the device to break dried pasta according to a first embodiment;

FIG. 2 is a front elevational view of FIG. 1;

FIG. 3 is a top elevational view of FIG. 1;

FIG. 4 is a bottom elevational view of FIG. 1;

FIG. 5 is a bottom perspective view of FIG. 4;

FIG. 6 is a top perspective view of the device to break dried pasta according to a second embodiment;

FIG. 7 is a front elevational view of FIG. 6;

FIG. 8 is a top elevational view of FIG. 6;

FIG. 9 is a bottom elevational view of FIG. 6; and,

FIG. 10 is a bottom perspective view of FIG. 9.

The ornamental design that is claimed is shown in solid lines in the drawings. The portions of the device to break dried pasta in broken lines are shown for illustrative purposes only and form no part of the ornamental design that is claimed. The separation of the device to break dried pasta by a curly bracket indicates indeterminate height.
